LUGGAGE CASE

John B. Humphries, Stamford, Conn., assignor to The
Excelsior Hardware Company, Stamford, Conn.

Filed Dec. 17, 1962, Ser. No. 72,879

Term of patent 14 years

(Cl. D87—5)

FIGURE 1 is a perspective view of a luggage case embodying my new design;

FIGURE 2 is an enlarged fragmentary top plan view with the handle omitted for convenience of illustration;

FIGURE 3 is an enlarged fragmentary side elevational view;

FIGURE 4 is a sectional view taken on the line 4-4 of FIG. 3;

FIGURE 5 is a sectional view taken on the line 5-5 of FIG. 3;

FIGURE 6 is a sectional view taken on the line 6-6 of FIG. 3; and

FIGURE 7 is an enlarged fragmentary top perspective view thereof.

The dominant features of the design reside in the solid line portions of the figures.

I claim:

The ornamental design for a luggage case, substantially as shown and described.
